UNITED STATES PATENT OFFICE.

FRANK H. FARRIS, OF MEDFORD, OKLAHOMA.

BOOK-SUPPORT.

1,268,946.

Specification of Letters Patent. Patented June 11, 1918.

Application filed May 18, 1917. Serial No. 169,516.

To all whom it may concern:

Be it known that I, FRANK H. FARRIS, a citizen of the United States, residing at Medford, in the county of Grant and State of Oklahoma, have invented certain new and useful Improvements in Book-Supports; and I do hereby declare the following to be a full, clear, and exact description of the invention, such as will enable others skilled in the art 10 to which it appertains to make and use the same.

This invention relates to improvements in a book support and has for one of its objects the provision of a device of this character, 15 which is capable of supporting books of several sizes and kinds and at various positions.

Another object of this invention is to provide a device of this character, which is constructed from a single length of material 20 bent into a construction, which may be readily converted into several forms for supporting several kinds of books and in different positions.

A still further object of this invention is 25 the provision of a book support of the above stated character, which shall be simple, durable and efficient, and which may be manufactured and sold at a comparatively low cost.

With these and other objects in view as 30 will become more apparent as the description proceeds, the invention consists of certain novel features of construction, combination and arrangement of parts as will be herein- 35 after more fully described and claimed.

For a complete understanding of my invention, reference is to be had to the following description and accompanying drawings, in which:

Figure 1 is a perspective view of a book support constructed in accordance with my invention, illustrating a book being supported vertically thereby,

Fig. 2 is a perspective view of the book 45 rack converted to support a note book or the like,

Fig. 3 is a perspective view of the book rack converted to support a book horizontally,

Fig. 4 is a top plan view of the book rack. Referring in detail to the drawings, the numeral 1 indicates as an entirety, a book rack, which is constructed from a single length of material, preferably stout wire, 55 which may or may not be enameled to add to the appearance of the device.

The single length of wire is first bent into substantially V-shaped formation as shown at 2 having mounted upon the apex portion thereof, a rubber pad or tube 3, to form a non-slipping foot for the device when supporting a book vertically and also for forming a portion to engage a book when supported horizontally to prevent the book from slipping thereon. The arm portions of the V-shaped member 2 are bent rearwardly and parallel with each other as at 4 for co-operating with the V-shaped portion in forming an efficient base to the device. The ends of the portions 4 converge upwardly and forwardly to a point as shown at 5 whence they extend upwardly in parallel relation to form vertically supporting arms 6, which are bent at right angles to form horizontally supporting arms 7, which are bent upon themselves to form spaces 8 for receiving the back and front of a book as shown in Fig. 1. The ends of the horizontal supporting arms after being bent upon themselves are bent to form hooks 9, which are adapted to be hooked together as shown in Fig. 2 for the purpose of supporting a note book 10 thereon. The bends between the portions 4 and 2 have mounted thereon, rubber pads or tubes 11 and rubber tubes or pads 12 are positioned upon the vertically supporting arms 6 and also are positioned upon the horizontal supporting arms 7.

When it is desired to support a ledger or other large book as shown at 13, in Fig. 1, the V-shaped portion 2 and the parallel portion 4 are positioned upon a table or like support whereby the vertically supporting arms 6 are supported or disposed vertically. The hinged portion 14 of the book 13 has its lower end disposed against the pad 3, which will prevent the lower edge of the book from slipping forwardly. The vertical supporting arms 6 are then moved apart to permit the front and back of the book 13 to be disposed within the spaces 8, also accompanied with the leaves of the book so that the book is supported in a vertical position, permitting any one of the pages to be read or copied therefrom.

When it is desired to support the note book 10, the hooks 9 are moved into engagement with each other, causing the vertically supporting arms 6 to converge and intersect each other as clearly shown in Fig. 2. The hinged portion 15 of the note book 10 is placed over the portions 16 of the hori-

horizontal supporting arms 7 so that the front and back of the note book 10 are disposed toward each other, which exposes the pages of the note book in view of the reader, and 5 also permitting the pages to be turned and passed downwardly between the spaces 8 when desiring to read the next page.

When it is desired to support a ledger or other large book in a horizontal position as 10 shown in Fig. 3, the hooks 9 are engaged with each other and the device is disposed horizontally so that the pads 11 and the curved portions 17 within the horizontal supporting arms 7 engage the desk or support, which support the vertically supporting arms 6 horizontally, permitting the hinged portion of the book 18 to rest upon the supporting arms 6 where they intercross 15 each other as clearly shown in Fig. 3 and the other end of the hinged portion of the book to rest upon the pad 3 upon the apex of the V-shaped member 2. The front and back of the book 18 is then disposed against the upwardly and forwardly converging portions 5, whereby the book 18 is supported in a horizontal position and which will permit the leaves of the book to be readily turned when desired.

While I have shown and described the 30 preferred embodiment of my invention, it will be understood that minor changes in construction, combination and arrangement of parts may be made without departing from the spirit and scope of the invention 35 as claimed.

Copies of this patent may be obtained for five cents each, by addressing the "Commissioner of Patents, Washington, D. C."

Having thus described my invention, what I claim is:

1. A book support comprising a base, vertical supporting arms formed on said base, horizontal supporting arms carried by the 40 vertical supporting arms, and being bent upon themselves to form a space for receiving the front and back of a book, and means for connecting the horizontal arms together to permit the device to support a book horizontally and also to support a note book vertically.

2. A book rack comprising a single length of material having a substantially V-shaped portion, the ends of the arm portions of the 50 V-shaped portion being bent rearwardly and parallel to coöperate with the V-shaped portion in forming a base, the ends of the parallel portions being bent to converge upwardly and forwardly and later bent upwardly to form vertically supporting arms, the ends of the vertical supporting arms being disposed at right angles in a horizontal plane thereto to form horizontally supporting arms having their free ends bent 55 to form hooks, said hooks adapted to be interlocked with each other for supporting a note book and for supporting a book horizontally.

In testimony whereof I affix my signature 60 in presence of two witnesses.

FRANK H. FARRIS.
